UNITED STATES PATENT OFFICE.

EMIL HALLGREN, OF BELLEVUE, PENNSYLVANIA.

CRUCIBLE-FURNACE.

1,138,866.

Specification of Letters Patent.

Patented May 11, 1915.

Application filed November 14, 1914. Serial No. 872,165.

To all whom it may concern:

Be it known that I, EMIL HALLGREN, a citizen of the United States, residing at 304 Riverview, Bellevue, in the county of Allegheny and State of Pennsylvania, have invented certain new and useful Improvements in Crucible-Furnaces, of which the following is a specification.

The present invention relates to new and useful improvements in crucible melting furnaces.

One object of the invention is the provision of a furnace including a melting chamber with stationary walls as well as a stationary arched roof, the said walls being supported upon a suitable base plate provided with an opening through which a movable bottom, upon which the crucibles stand, can be removed in a vertical plane.

Another object of this invention is the provision of a furnace of the above specified type, wherein a great saving of labor is made possible, and in which the hardships attendant to the present class of crucible steel melting furnaces is eliminated.

Another object of the present invention is the provision of a furnace such as described, in which considerable saving in fuel is provided for, on account of the closed construction of the melting chamber, individually controlled and shut off by suitable valves from the air, gas and stack connections.

A further object of the invention is the provision of a furnace such as above specified, in which the cost for repairs will be reduced to the minimum, on account of the nature of the construction thereof, there being no loose tiles in the walls and all of the movable parts being thoroughly locked in position.

Still another object of the present invention is the provision of a furnace in which the waste or loss of crucibles with their valuable contents is prevented, by the safe and steady movements of the bottom with the said crucibles supported thereon which can be more conveniently handled when the said bottom is removed.

A further object of the present invention resides in the provision of a furnace, wherein, by the arrangement of the melting-chamber and furnace ports, and the designing thereof to hold more crucibles, the output thereof will be materially increased.

A still further object of this invention is

to improve and simplify devices of this character, rendering them comparatively simple and inexpensive to manufacture, reliable and efficient in use, and readily operated.

It should be understood in this connection, that various minor changes in the specific details of construction can be resorted to within the scope of the appended claim, without departing from the spirit or sacrificing any of the advantages of the invention.

With the above and other objects in view, the present invention resides in the novel features of construction, formations, combinations and arrangements of parts to be hereinafter more fully described, claimed and illustrated in the accompanying drawings, in which:

Figure 1 is a vertical sectional view, taken through the center of a melting chamber, in a furnace constructed in accordance with my invention, on the line A—A of Figs. 3, 4, 5, 6, and 7. Fig. 2 is a vertical sectional view, taken through the melting chamber wall and regeneration chambers, on the line B—B of Fig. 3. Fig. 3 is a horizontal view, taken through the melting chamber on the line C—C Fig. 1. Fig. 4 is a horizontal sectional view taken through below melting chamber. Fig. 5 is a horizontal sectional view taken through port holes and melting chamber. Fig. 6 is a vertical sectional view taken through the center of melting chamber indicated by the section line D—D in Figs. 1, 2, 3, 4, and 5. Fig. 7 is a vertical sectional view, taken on the line E—E of Fig. 1.

Referring to the accompanying drawings by like characters of reference throughout the several views, the numeral 1 denotes a melting chamber of the furnace, which is supported by a metal base plate 2, having an opening therein closed normally by the base bottom 3, which has attached to its upper side the bottom lining 4. The opposite sides of the melting chamber are provided with port openings 5—5, which are in communication with the opposite vertical flues 6—6 which constitute the mixing chambers. The opposite right and left hand air flues, are shown at 7 and 8, and connect each of the vertical flues 6, with the right and left hand air regeneration chambers 11 and 12 respectively. The right and left hand gas flues 9 and 10 are shown clearly

in the drawings and connect the before mentioned flues 6, with the right and left hand gas regeneration chambers 13 and 14. The above described air flues 7 and 8 are controlled by the valves 15, while the gas flues 9 and 10 are controlled by similar valves 16, in order that the air and gas can be shut off from the melting chamber 1. When the bottom 3 is to be lowered therefrom, this bottom 3 and 4 is supported and actuated by the plunger head 17, attached to the plunger rod 18, which has a vertical cylinder 19 secured to main base 20. The plunger head slides along the vertical guides 21 and 15 is controlled at the will of the operator, to raise or lower the bottom 3 and 4.

The plunger head 17 has guides 17^a thereon, which engage the vertical columns 21, which retain the head 17 in proper position during its vertical movement, while similar columns or standards 22, assists in supporting the base plate 2 and consequently the melting chamber 1.

Horizontal guides 23 extend beneath the melting chamber 1 as shown in Figs. 1 and 6 and support a cross bar 24, which is designed for interlocking engagement with the number 3, having a flange 24^a when the same is lowered at which time a similar flange 3^a formed upon the base plate 3 rests upon the guides 23 as clearly apparent from an inspection of Fig. 6. A horizontal cylinder 25 is mounted below the operator's platform 26. This cylinder corresponds to the vertical cylinder 19 and is provided with a plunger therein which is attached to the cross head 24.

When in operation the crucibles are placed upon the bottom lining 4, within the melting chamber 1 and the valves 15 and 16

controlling the supply of air and gas are opened and the bottom of the melting chamber is retained in its closed position until the operator desires to remove the said crucibles, the air and gas are then turned off, 45 and the bottom 3 and 4, upon which the crucibles are carried is lowered, until the same rests upon the horizontal guides, with the locking flange thereof in interlocking engagement with the cross bar 24, which is 50 then operated to draw the said bottom and crucibles to a point adjacent the platform 26.

Having thus fully described this invention, what I claim as new and desire to protect by Letters Patent is:

In a furnace of the character described, a melting chamber having an open lower end, stationary sidewalls and solid roof for said melting chamber, a vertically movable 60 bottom, closing said open lower end, a plunger supporting said movable bottom, means for actuating the plunger to move said bottom away from and toward said opening, horizontal guides disposed below the melting chamber for supporting the bottom when in its lowermost position, a cross head slideable upon the guides, in interlocking engagement between the cross head and bottom, means for actuating the cross head 70 to move the bottom horizontally out of the vertical path of movement and a platform in the line of horizontal movement of the bottom.

In testimony whereof, I affix my signature in presence of two witnesses.

EMIL HALLGREN.
